UNITED STATES PATENT OFFICE.

FREDERICK WATERHOUSE, OF WALLINGFORD, CONNECTICUT, ASSIGNOR
TO HALL, ELTON & CO., OF SAME PLACE.

DESIGN FOR A SPOON OR FORK HANDLE.

SPECIFICATION forming part of Design No. 12,841, dated March 28, 1882.

Application filed February 13, 1882. Term of patent 3½ years.

To all whom it may concern:

Be it known that I, FREDERICK WATERHOUSE, of Wallingford, in the county of New Haven and State of Connecticut, have invented a new Design for Spoon or Fork Handles; and I do hereby declare the following, when taken in connection with accompanying drawing and the letters of reference marked thereon, to be a full, clear, and exact description of the same, and which said drawing constitutes part of this specification and represents a front view.

This invention relates to a design for the handles of spoons, forks, and like articles of table service; and it consists in the configuration and ornamentation as shown in the accompanying illustration.

The sides of the handle are parallel from the bowl for about one-third the length of the handle, thence gradually expanding to the end, where it terminates in a segment shape. At the point where the expansion begins there is on the face a rose ornament, *a*, with an ornamented transverse band, *b*, below and *c* above. Starting from the point *a* at one side, an ornamented band, *d*, runs diagonally upward, terminating at a transverse ornamented band, *e*. Above this last band is another transverse band, *f*, with a scallop ornament below it and a semicircular panel above, the face of which is ornamented by scroll-work. From this last ornament to the end the surface of the handle is plain, all as shown in the accompanying illustration.

35
I claim—
The design for the handle of spoons and forks, consisting of the rose ornament *a*, transverse bands *b* *c*, gradually expanding therefrom and terminating in a segment shape at the end, an ornamented band, *d*, extending diagonally across the face of the handle, above the band *c*, to a transverse ornamented band, *e*, and the ornamented transverse band *f* and semicircular panel, as shown in the accompanying illustration.

FREDERICK WATERHOUSE.
